UNITED STATES PATENT OFFICE.

BURCHARD D. THOMPSON, OF CYCLONE, PENNSYLVANIA, ASSIGNOR OF ONE-HALF TO
J. L. YERDON, OF BRADFORD, PENNSYLVANIA.

FUEL-CONTROL MEANS FOR INTERNAL-COMBUSTION ENGINES.

Application filed August 27, 1926. Serial No. 131,968.

This invention relates to means for intermittently feeding fuel under pressure to an internal combustion engine.

The principal objects of the invention are
5 to make the lifting of the inlet valve from its seat, positive and instantaneous, to compensate for wear between such operating parts, and to be able to vary the intermittent action of the valve lifting means as to
10 the time of admission of fuel to the combustion chamber.

To this end the invention comprises the novel arrangement, combination and construction of parts hereinafter described and
15 shown in the accompanying drawings, in which—

The figure is a view partly in section of an internal combustion engine showing the invention applied thereto.

20 An internal combustion engine of the stationary type is shown diagrammatically to consist of a combustion chamber 2 provided with a detachable dome shaped head 3, secured thereto by bolts 4.

25 A nozzle 5 threaded or otherwise secured to the wall of the dome 3 permits fuel to be injected under desired pressure to the explosion chamber.

The inner end of the nozzle 5 is provided
30 with valve 6 ground into the bevelled end of the nozzle, and having a stem 7 projecting without the nozzle. A stuffing nut 8 prevents escape of fuel under pressure. The protruding end of the stem 7 is fitted with
35 a collar 9 and a spiral spring 10 surrounds this part of the valve stem, and bears against collar 9 and stuffing nut 8 thus tending to keep valve 6 on its seat in closed position.

The end of the valve stem 7 beyond the
40 collar 9 is bevelled and is engaged by a wedge shaped cam 11, carried on push rod 12 suitably supported from the cylinder as at 13. Cam 11 is slidably contained in an opening 14 of fixture 15, attached to dome head 3 in any desired manner. Cam 11 is so proportioned in relation to the space 14 that it is permitted a slight vertical movement upon being given an impact against the tension of the spring 10.

45 At the bottom of fixture 15 is provided a pivoted impact element having a contact arm 16 carrying a boss 17, and a trigger arm 18 extending at substantially a right angle thereto. This latter is engageable by

a trip 19 supported upon the rod 25 in a 55 pivotal manner so that movement of the trip 19 to the left will positively move the trigger arm 18 but movement to the right will allow the trip 19 to pass under the trigger without moving the latter. A block 20 is carried by an adjustment rod 21 slideable in bearing 22 and movable by rotation of the hand wheel 23. The rod 21 is threaded through the support 24 secured to rod 25 so that movement of the hand wheel 60 65 23 will cause a corresponding movement either to the right or left of the trip 19. Rod 25 may be run from an eccentric off the crank shaft or from a cam shaft in the usual manner, and as is well known.

70 A spring 26 maintains boss 17 in contact with the under part of the cam 11 so that when trip 19 passes to the left against trigger arm 18 and then beyond so as to clear the same, the spring 26 exerts its tension and the boss is made to sharply contact with the cam 11. This in turn imparts light vertical movement to the inlet valve and admits a proper amount of fuel under pressure to the combustion chamber.

75 The rod 12 may through the instrumentality of hand wheel 27 be made to enter or recede from the space 14 so as to insure contact between the cam 11 and the end of the valve stem 7.

80 Obviously by moving trip 19 to right or left will either retard or advance the opening of the inlet valve.

85 Fuel may be supplied under requisite pressure through feed line 28 from any desired source and in any desired manner.

It will be noted that such instrumentalities as above described provide for intermittent feeding of fuel under pressure to the combustion chamber of such an engine 95 where it is ignited as for instance by a spark plug 29.

The means herein described likewise provide for instantaneous lifting of the inlet valve to release the fuel held back thereby. 100 Obviously the tension of the spring 10 must be greater than the pressure used on the fuel line. Such instantaneous feeding of the fuel makes toward efficiency of vaporization, and combustion and therefore of engine 105 operation and usefulness.

I claim:

1. In combination an internal combustion

22
engine cylinder, means to supply fuel thereto including an inlet valve held in closed position by means of a spring impact, means to lift said valve from its seat, reciprocating means to intermittently trip said impact means, said impact means including a cam movable across the axis of the valve stem and in contact with said stem.

2. In combination an internal combustion engine cylinder, means to supply fuel thereto including an inlet valve held in closed position by means of a spring impact, means to lift said valve from its seat, reciprocating means to intermittently trip said impact means, said impact means including a pivoted member having an impact arm and a

trigger arm, said trip engaging said trigger arm to open said valve.

3. In combination an internal combustion engine cylinder, means to supply fuel thereto including an inlet valve held in closed position by means of a spring impact, means to lift said valve from its seat, reciprocating means to intermittently trip said impact means, said impact means including a pivoted member having an impact arm and a trigger arm, said trip engaging intermittently said trigger arm, and means to adjust the time of contact between said trip and said trigger arms.
